DESIGN FOR A FRUIT JUICE EXTRACTOR

William P. Koch, Chicago, Ill., assignor to Chicago Die Casting Manufacturing Company, a corporation of Illinois

Application June 6, 1940, Serial No. 92,856

Term of patent 7 years

To all whom it may concern:

Be it known that I, William P. Koch, a citizen of the United States, residing in Chicago, county of Cook, State of Illinois, have invented a new,
original, and ornamental Design for Fruit Juice Extractors, of which the following is a specification, reference being had to the accompanying drawing, forming part thereof.

Figure 1 of the drawing is a perspective view
of a fruit juice extractor embodying my design;
and Figure 2 is a rear view of said fruit juice
extractor.

I claim:

The ornamental design for a fruit juice ex-
tractor, as shown.

WM. P. KOCH.
